CODED TRACK CIRCUIT SIGNALING
SYSTEM

J Donald Hughson, Rochester, N. Y., assignor to
General Railway Signal Company, Rochester,
N. Y.

Application February 13, 1946, Serial No. 647,270

4 Claims. (Cl. 246—41)

1

The present invention relates to automatic block signalling systems for railroads using coded track circuits, and more particularly pertains to an improved form of coded track circuit for use in such signalling systems.

The conventional coded track circuit block signalling system provides for the application of current impulses at the exit end of each coded track circuit section with intervals between the successive pulses which have been conveniently termed "off-periods." These time spaced impulses are transmitted at different distinctive code rates in each track section in accordance with the traffic conditions in advance of that section, and comprise what are termed driven codes.

At the entrance end of a conventional coded track circuit section, a code following track relay is connected across the rails of that section to receive the driven code impulses and act upon suitable decoding apparatus which is distinctively governed in accordance with the particular rate of the driven code then being received. This decoding apparatus acts to govern the indications of the associated signal in accordance with traffic conditions in advance of that signal, and also acts to select the code rate to be applied to the next track section in the rear.

A block signalling system using such conventional coded track circuits encounters several practical difficulties in actual practice. For example, it may happen that the presence of a foreign current in a track section will cause improper operation of the code following track relay. Such foreign current may be due to the leakage of current from some power line or may be due to the electrolytic action occurring in the track circuit itself because of the various chemical constituents in the ballast and the presence of a proper amount of moisture under varying weather conditions.

The presence of a foreign current, regardless of its source or cause, in some cases entirely prevents the proper operation of the track relay of a section in response to the application of code pulses at the exit end of that section. In other cases, the presence of foreign current together with the coded current causes the track relay to become so magnetically saturated as to render the relay slow in responding to the off-periods between successive impulses thus distorting the code pattern received. It will be readily appreciated that the duration of the off-periods of a code should be approximately equal to the impulse periods of that code in order to have a symmetrical effect upon the decoding apparatus which

2

is distinctively responsive to the different code rates. However, it should be understood that the particular time ratio selected as between the impulse and space periods is dependent upon the character of the decoding apparatus, but regardless of the particular ratio selected, it is essential to maintain the proper ratio of different track circuit conditions in order to give the optimum results.

10 A further difficulty is encountered in coded track circuits due to the wide variation in the ballast leakage of the track circuit. With high ballast resistance conditions i. e. when the ballast is dry, the track circuit may be adjusted to give the proper amount of current at the track relay end so that the code following track relay will properly respond to the code pulses applied at the exit end. However, a change in weather conditions i. e. the presence of moisture in the ballast, causes the ballast resistance to decrease so as to draw current away from the code following track relay at the entrance end to the section. In such a case, even though the track relay receives sufficient current to effect its operation, it is shunted by the low ballast resistance which renders it slow in its release time since the stored magnetic energy in the relay results in an inductive current which flows through the track relay and the ballast leakage resistance. This condition distorts the operation of the code following track relay with respect to the actual time spacing and duration of the pulses impressed on the track circuit. For example, if the coding pulses on the track circuit have substantially the same duration as the time spaces between pulses, the track relay with its slow release operation would distort the effect of these impulses on the decoding apparatus. In other words, the contacts of the track relay would remain in one position for the pulse period longer than in the opposite position for the time space, so that the effect would not be uniform on the decoding apparatus. This distortion may be so severe as to cause failure of the decoding apparatus to properly respond.

45 On the other hand, the usual method of adjusting coded track circuits is to supply sufficient energy to the track circuit to cause operation of the track relay under the lowest resistance ballast conditions expected to occur, then as the ballast dries out and its resistance increases a considerable added amount of energy is supplied to the track relay. In some cases this will result in a sufficient over-energization of the track relay as to substantially increase its release time and 50 distort the time ratio of the code pulses to the

separating spaces. If the conditions are severe enough, it may happen that the track relay will not have sufficient time to release before the next successive code pulse is received. As above pointed out, any delay of the track relay in releasing at the end of a code pulse applied to the track circuit will have an adverse effect upon the decoding apparatus.

In view of the above and other conditions which may be encountered in practice, it is proposed in accordance with the present invention to provide a coded track circuit organization which will be responsive to the code impulses but will be unresponsive to the presence of steady foreign currents in the circuit as well as being so organized as to provide for the proper time response of the code following the track relay regardless of varying ballast conditions.

Generally speaking and without attempting to define the nature or scope of the present invention, it is proposed to accomplish the purposes of the present invention by providing a coded track circuit having a code following track relay inductively coupled to the track circuit by a suitable transformer and having improved means for applying code pulses to the track circuit. It is proposed that the code following track relay shall be of the two position stick or stay-where-put type, whereas the code applying apparatus is so organized as to cooperate with the code receiving apparatus in a manner to materially reduce the amount of current that is required to be broken through the code transmitting contacts.

With this organization, the track relay is responsive only to the different current changes in the track circuit i. e., when an impulse is applied or removed. The current change in the primary winding of the transformer upon the application of a code impulse causes a current pulse to flow in one direction through the track relay, whereas the termination of such a code impulse causes a decrease in current in the primary winding of the transformer to thereby cause a current pulse of the opposite polarity to flow through the track relay. In this way, the track relay is operated to its opposite positions at the beginning and end of each code impulse applied to the track circuit. Such an organization is practically immune to the presence of foreign direct current in the coded track circuit, and various changes in ballast conditions have very little effect upon the time of operation of the track relay.

Thus, it will be readily apparent that one object of the present invention is to provide a more sensitive and reliable code following track relay organization for use in coded track circuits which organization overcomes certain of the difficulties encountered in actual practice.

Other objects, purposes and characteristic features of the present invention will be in part obvious from the accompanying drawings and in part pointed out as the description of the invention progresses.

In describing the invention in detail, reference will be made to the accompanying drawings, in which like reference characters designate corresponding parts throughout the several views, and in which:

Fig. 1 shows diagrammatically one form the present invention may take in a coded track circuit by using a two-position magnetic stick type relay inductively coupled to the track circuit;

Fig. 2 shows diagrammatically another form the present invention may take by the use of a

two-position mechanically held relay of the neutral type inductively coupled to the track circuit;

Fig. 3 illustrates diagrammatically another form the present invention may take by the use of a neutral differential stick relay inductively coupled to the track circuit;

Fig. 4 illustrates diagrammatically a modified code impulse applying organization; and

Fig. 5 illustrates one specific form of transformer that may be employed for more advantageously accomplishing the objects of the present invention.

For the purpose of simplifying the illustration, and facilitating in the explanation, the various parts and circuits constituting the embodiment of the invention have been shown diagrammatically and certain conventional illustrations have been employed, the drawing having been made more with the purpose of making it easy to understand the purpose and mode of operation than with the idea of illustrating the specific construction and arrangement of parts that would be employed in practice.

Thus, the various relays and their contacts are illustrated in a conventional manner, and symbols are used to indicate connections to the terminals of batteries or other suitable sources of electric current instead of indicating all the wire connections to these terminals. The symbols (+) and (-) are employed to indicate the positive and negative terminals respectively of suitable batteries or other sources of direct current, and the circuits with which these symbols are employed are assumed to always have current flowing in the same direction, although it is to be understood that in some cases alternating current may be substituted for the direct current if desired, and in such cases the (+) and (-) symbols are to be considered as indicating the relative instantaneous polarities of the alternating current. In certain instances, batteries and their associated connections are shown in detail instead of using symbols so as to make the circuit organization more clear and definite.

With reference to Fig. 1 of the accompanying drawing, a stretch of track has been shown as divided into track sections by suitable insulated joints of which the track section 2T has been shown completely and track sections 1T and 3T in part only. The color light type signals 2 and 3 are shown at the entrance ends of the track sections 2T and 3T respectively. These signals may of course be of any other suitable type desired.

At the exit end of the track section 2T, a code transmitting relay 3CP is provided with a contact 5 which in a back contacting position closes a circuit through wire 23 to shunt the track section 2T, but in a front contacting position connects the track battery 6 and resistor 7 in series across the track section to apply a code pulse of energy. This code transmitting relay 3CP is controlled through front contact 8 of relay 3H so as to apply a code of the 180 pulse per minute type by reason of the operation of an associated coder contact 180C; while the closure of back contact 8 of relay 3H connects the relay 3CP to the coder contact 75C to effect the application of a code of the 75 code pulse per minute rate. This relay 3H is governed through a track relay 3TR inductively coupled to the track section 3T by the transformer 3TF as more specifically described in connection with the apparatus at the entrance end to the track section 2T.

Referring to the left hand end of the track section 2T conveniently referred to as the en-

trance end of the track section, assuming east bound traffic to be the normal direction of train movement, it will be seen that the track relay 2TR is inductively coupled through a transformer 2TF to the track rails of the track section 2T. This transformer 2TF is an iron core transformer having primary winding 9 and a secondary winding 10.

It should be understood that the transformer 2TF may be of any suitable construction of the usual type as illustrated by the conventional transformer symbols. However, in order to obtain the optimum results from the track circuit organization of the present invention, it is preferable to have the primary-secondary turn ratio properly selected to match the surge impedance of the track relay 2TR with the surge impedance of the track circuit when the track circuit is at its lowest ballast resistance condition. This matching of the surge impedance under the most adverse conditions is desirable to obtain the proper operation of the track relay under such conditions since the maximum transfer of energy is effected when the impedances are thus matched. However, under other conditions i. e. when the ballast resistance increases, the supply of energy to the primary winding of the transformer 2TF will be greater so that even though the impedances are not exactly matched, there will be a sufficient transfer of energy to the track relay 2TR to effect its operation.

It is also preferable that the transformers, such as transformer 2TF, should be of the open magnetic circuit type as illustrated in Fig. 5 rather than of the usual closed magnetic circuit type. However, it should be understood that such structure is not required for the operation of the present invention; but, since it improves the timing characteristics of the organization, it is considered to be a preferred form and will be discussed in greater detail, as the description progresses.

Each track relay, such as track relay 2TR, is of the two-position magnetic stick type, that is, it is a relay of the polarized type having contacts which are actuated to one position or the other depending upon the polarity of the energy applied to the relay, and these contacts remain in their last actuated positions until energy of the opposite polarity is applied. Such a magnetic stick type relay may take different forms, one such relay having been disclosed in the prior patent to Hailes et al., Patent No. 1,929,094 dated October 3, 1933. However, the more rugged type of track relay is usually desirable such as having the general structural characteristics disclosed in the Patent No. 2,360,664 granted October 17, 1944, to O. S. Field. This Field patent structure is shown as being a polarized biased relay, but such relay can be readily changed to a two-position magnetic stick type relay by merely removing the biasing spring, and in this way the magnetism provided by the permanent magnets causes the armature to remain in its last operated position until the relay windings are energized with an opposite polarity.

The track relay 2TR is provided with a contact 11 which energizes the opposite halves of a split primary winding of a decoding transformer 12. The secondary winding of this decoding transformer is also provided with a mid-tap connected through the winding of a home relay 2H to a rectifying contact 13 of the relay 2TR. Thus, as the relay 2TR operates its contacts 11 and 13 to their opposite positions, inductive pulses are

caused to flow in the same direction through the windings of the relay 2H. This causes the relay 2H to be picked up when the track relay 2TR is operated at either the 75 code rate or the 180 code rate.

The decoding transformer 12 is also provided with secondary winding 14 which through condenser 15 supplies the primary winding of a transformer 16 with inductive pulses and this circuit is so tuned as to be responsive to the 180 code rate alone and when that code rate is supplying the secondary winding of the transformer 16 sufficient energy is supplied through the rectifier unit 17 to effect the picking up of the relay 2D. In other words, the relay 2H is picked up during the reception of a code of either a 75 or 180 code rate, but the relay 2D is picked up only upon the reception of a code of the 180 code rate.

Since the response of the relay 2D is dependent upon a tuned circuit, and a tuned circuit responds more readily to one particular frequency, it can be readily seen that it is desirable to provide substantially equally spaced inductive pulses for the tuned circuit during the reception of the 180 code rate.

When the relays 2H and 2D are both picked up, front contacts 20 and 21 are closed to energize the green lamp G of the signal 2; but when the relay 2D is deenergized, as will occur during the reception of a 75 code rate, the front contact 20 supplies energy through back contact 21 to energize the yellow lamp Y of the signal 2. The absence of all code allows the relay 2H to release, as will occur during the presence of a train in the track section 2T, to close the back contact 20 and energize the red lamp R of the signal 2. It can thus be seen that the 180 code rate in the track section 2T causes a green aspect to be displayed by the signal 2, while a 75 code rate in the track section 2T causes a yellow aspect to be displayed by the signal 2.

The presence of a 75 or 180 code rate in the track section 2T effects the picking up of the relay 2H to close front contact 22 and cause a 180 code to be applied to the track section 1T in the rear, but when no code is being received, and the relay 2H is deenergized, back contact 22 is closed so as to apply a 75 code rate to the track section 1T in the rear.

The different code rates are provided by coding contacts 180C and 75C which may be of any suitable type, that is, they may be motor driven or they may be code oscillators of the type disclosed, for example, in the prior Patent No. 2,351,588 granted to O. S. Field, June 20, 1944. The coding contacts 180C and 75C are assumed to produce 180 code pulses per minute and 75 code pulses per minute respectively, although it is to be understood that different code rates may be employed if desired.

Regardless of the particular code rate being applied to the track section 2T, which is of course typical of all of the track sections of the block signalling system, the application of each impulse to the track rails of track section 2T causes a current flow through the primary winding 9 of the transformer 2TF. During the rise in current through the primary winding, an impulse is created in the secondary winding 10 in such a direction as to cause the contacts 11 and 13 of the relay 2TR to be actuated to left-hand positions in which they are held by the inherent polarized characteristics of the relay even though current flow through the track relay 2TR ceases. In other words, while the current impulse is rising to its

full value in the primary winding 9, a momentary current pulse is inductively produced in winding 10 during such rise, but when the track impulse current reaches a steady value the current flow in the secondary winding 10 ceases.

Upon the cessation of a code impulse in the track circuit by reason of the opening of front contact 5 of relay 3CP and the shunting of the track circuit through the connection 23, the current decrease in the primary winding 9 causes a momentary pulse in the secondary winding 10 in such a direction as to actuate the polar contacts 11 and 13 to their right-hand positions.

With this inductive coupling of the track relay to the track circuit, it is apparent that the relay receives a momentary pulse at the beginning of each code pulse applied to the track circuit and another momentary pulse at the end of each code pulse applied to the track circuit. Since these pulses occur in succession and are alternately of opposite polarity, the polarized track relay is operated to its opposite positions alternately at a rate determined by the rate of the code pulses applied to the track circuit at that time.

Although the conventional transformer of the completely closed core type will effect the desired inductive coupling of the track relay to the track circuit, and provide for the response of the track relay at the beginning and end of each code pulse, it will be appreciated that a completely closed core does not allow the decay of flux therein as rapidly as a core having an air gap. Because of this delayed collapse of the magnetic flux in a closed magnetic circuit, the inductive pulse supplied to the track relay would also be delayed and result in the delayed operation of the track relay. If the present invention is applied to a relatively simple track circuit organization, as shown in Fig. 1, this delayed response of the track relay due to a closed magnetic circuit type transformer is of no particular consequence, since the track relay is operated uniformly with a certain response time following the beginning and end of each code pulse regardless of varying track circuit conditions, and since it is possible to so select the duration of the code pulses so as to give the track relay the proper timing response with respect to the decoding apparatus.

However, if the features of the present invention are to be applied to a more complex track circuit organization employing inverse codes, as disclosed in the Patent No. 2,353,930 granted to F. X. Rees, July 18, 1944, it is essential to have the track relay operate with as quick a response as possible immediately following the application or removal of a code pulse from the track circuit. This is desirable so as to provide sufficient time between the release of the track relay and the next code pulse for the transmission of the intervening inverse code pulse. In such an organization, the track circuit shunt 23 of Fig. 1 would be replaced by an inverse code receiving relay, and suitable means at the entrance end of the track circuit 2T, would be employed to disconnect the primary winding 9 from the track circuit momentarily for the application of inverse code pulses to the track circuit, as shown in detail in the above-mentioned prior Patent No. 2,353,930.

With this more complex coding track circuit organization, it is especially desirable to use a transformer, such as illustrated in Fig. 5 of the drawings, to improve the time of response of the track relay. This Fig. 5 shows the core structure of the transformer 2TF as being formed of E-shaped laminae so stacked as to provide an open magnetic

circuit. In other words, the magnetic path formed by the core structure includes an air gap. The windings 9 and 10 are mounted upon the middle leg of the E-shaped core structure as indicated. This particular structure, used in the coded track circuit organization as shown in Fig. 2, acts to make the response of the track relay more rapid to the application and removal of code pulses. However, it should be noted that by properly selecting the size of the air gap in the open end of the magnetic circuit of the transformer, this timing relationship may be varied as desired with respect to the beginning and end of the code pulses applied to the track circuit.

In one embodiment of the present invention, it was found that a transformer of the above-described type having a primary-secondary winding ratio of one-to-one was very suitable for a typical track circuit. The secondary winding 10 was constructed of a suitable sized wire to give such winding the same ohmic resistance as the track relay 2TR, whereas the primary winding 9 was constructed of a suitable sized wire to give an ohmic resistance which when added to the ohmic resistance of its lead wire connections to the track circuit gave a total resistance substantially corresponding to the resistance of the track relay. This construction of transformer resulted in substantially decreasing the pickup and release times of the track relay as compared to a transformer with a completely closed magnetic circuit and having the same amount of iron with the same construction of windings.

The presence of a foreign steady potential of a limited value in the track section 2T merely causes current flow through the primary winding 9 of a steady nature, which has no effect on the track relay 2TR. Since the application of impulses to the track section 2T under such conditions still causes a rise in current flow through the primary winding 9 at the beginning of each current pulse, and a decrease in current flow through the primary winding 9 at the termination of each impulse, the track relay 2TR is caused to follow the applied code pulses without distortion. In other words, the pulses induced in the secondary winding 10 occur concurrently with the rise and fall of current in the primary winding 9 in synchronism with the application and removal of the pulses by the coding contact 5 independently of the presence of limited values of steady foreign current in the track section.

In the conventional track section where the track relay is connected directly across the track rails, it is apparent that even though there is a decrease of current in the track relay winding upon the termination of the impulse, the continued flow of some current through the track relay winding due to the presence of a foreign current will considerably retard the release of the contacts of the relay so as to materially distort the code pulses as reproduced by the code following track relay. In some cases, the foreign current may be so high as to actually maintain the track relay energized so that it will not follow the pulses at all.

Whereas, in the case of the present invention, values of foreign current, which would cause a conventional coded track circuit to cease operation, have practically no effect on its undistorted and reliable operation. In this connection, it will be noted that the values of foreign current which may be tolerated and still obtain proper operation will depend upon the various constants of the track circuit and apparatus employed, but

generally speaking the foreign current will have no practical effect upon the track circuit until such current is of such a high value as to materially magnetize the core of the transformer 2TF.

Similarly, as above mentioned briefly, the low resistance of the ballast of the track circuit under certain weather conditions acts as a shunt across the conventional track relay so as to maintain self-induced current in the winding of the track relay thereby holding its armature picked up for an appreciable time after termination of an impulse. In the present organization, the termination of an impulse and a change in current flow through the primary winding will cause a momentary impulse in the secondary winding to actuate the contacts of the track relay to the proper position, and any prolongation of such inductive condition due to the low ballast resistance does not adversely act on the track relay. In other words, the initial decay of current at the end of an impulse causes an immediate response of the track relay. Thus, very low resistance ballast conditions fail to produce the disadvantageous distortion of the code following track relay operation in the present invention, and this insures the proper response of the decoding apparatus to the different distinctive codes.

In some cases the foreign current will be due to some external source of energy, while in others it may be due to the electrolytic action occurring within the track circuit ballast connecting the two rails of the track circuit. In still other cases, it may happen that the track circuit acts somewhat similar to a storage battery so that continued application of code pulses will tend to build up a potential between the two rails of the track circuit. In such a case, the shunt 23 acts to dissipate the stored potential in the track circuit between code pulses so as to prevent the accumulation of any substantial potential across the track rails.

Regardless of the particular source of the foreign current in the track circuit, it is apparent that the shunt connection 23 will tend to dissipate any energy existing in the track circuit during the off-periods of the code then being applied. Thus, insofar as the shunt 23 acts to cause a reduction in foreign potentials across the track rails of the track circuit, it also causes a more rapid decrease in the current flowing through the primary winding 9 of the transformer 2TF. Since the intensity of the current pulse in the secondary winding 10 and track relay 2TR is dependent upon the rate of change of current in the primary winding 9, it is apparent that the shunt 23 contributes to the end of producing more substantial current pulses in the track relay to operate it to its opposite positions. However, it is to be understood that the track circuit of the present invention will operate within certain ranges of values and constants of the track circuit and apparatus without the shunt 23, which shunt 23 is provided for increasing the range of operation of the track circuit under certain conditions that may be encountered in practice.

With reference to Fig. 2 of the accompanying drawings, it is noted that the transformer 2TF has its secondary winding 10 connected to a relay 2TR² through a rectifier R1 and another rectifier R2. This track relay 2TR² has two windings 26 and 27, and is of the neutral mechanical stay-where-put type. In other words, when the winding 26 is energized, the contacts 11² and 13² are actuated to left hand positions, but when the winding 27 is energized these contacts are actu-

ated to right hand positions. When the contacts of this relay are operated to either position, they remain in that position until operated to the opposite position by reason of suitable mechanical means, such as a mechanical toggle arrangement, or the like.

Whenever an impulse is applied to the track circuit and the resulting pulse induced in the secondary winding takes place, such induced pulse flows through the rectifier R1 to energize the winding 26, but this pulse cannot flow through the winding 27 by reason of the connection of the rectifier R2 in its circuit. Similarly, upon the cessation of a code impulse in the track circuit, the resulting pulse produced in the secondary winding 10 flows through the winding 27 and rectifier unit R2 by reason of the polarity of such pulse and is prevented from flowing through the winding 26 by reason of the rectifier unit R1. For this reason the contacts 11² and 13² are actuated to their opposite positions alternately at a rate dependent upon the rate of the code pulses applied to the track circuit, and these contacts control the decoding apparatus the same as disclosed in Fig. 1. In other words, a second form of the invention contemplates a signalling system having coded track circuits such as shown in Fig. 1 but employing relays of the type disclosed in Fig. 2 in place of the magnetic stick type relays disclosed in connection with Fig. 1. This form of the invention operates in the same way as described in connection with Fig. 1, and gives the same advantageous features.

With reference to Fig. 3 of the accompanying drawings, it will be seen that a track relay 2TR³ is provided having two windings. This relay 2TR³ is a neutral type relay and its upper winding is connected to the secondary winding 10 of the transformer 2TF while its lower winding is connected through a stick contact 30 and resistor 31 to a suitable source of energy. Its contacts 11³ and 13³ are connected to decoding apparatus the same as shown in Fig. 1. In other words, this form of the invention contemplates a system the same as disclosed in connection with Fig. 1 but having a relay of the type shown in Fig. 3 substituted for the magnetic stick type relay 2TR shown in Fig. 1.

Upon the application of a code pulse to the track circuit, a pulse is induced in the secondary winding 10 of the transformer 2TF and this pulse flows through the upper winding of the track relay 2TR³ causing such relay to pick up. As soon as front contact 30 is closed a stick circuit is established through the lower winding 2TR³, and since the direction of energy by such pulse in the upper winding of the relay is the same as the direction of energization by the stick circuit, the relay remains picked up even though the momentary pulse flowing through its upper winding ceases.

Upon the termination of a code pulse in the track circuit a pulse is induced in the secondary winding 10 of transformer 2TF which is in the opposite direction to the pulse induced at the beginning of the code pulse of the track circuit. Such momentary energization of the track relay 2TR³ in the reverse direction acts to neutralize the magnetic flux produced by the stick circuit through its lower winding so that the contacts of the relay drop away and open the stick circuit coincident with the cessation of the pulse induced in the secondary winding 10 of the transformer. In this way the beginning of a code pulse in the track circuit causes the relay

$2TR^3$ to be picked up, while the termination of such code pulse in the track circuit causes the relay $2TR^3$ to be dropped away. This form of the invention is contemplated as having the same advantages and operations pointed out in connection with Fig. 1 which need not be repeated in detail.

Referring to Fig. 4 it is to be noted that the code applying apparatus shown in this form of the invention may be substituted for the code applying apparatus disclosed in Fig. 1. In other words, the shunt 23 of Fig. 1 may be removed and have substituted therefor a track battery 40 connected in series with a resistor 41. Each time the code transmitting relay $3CP^4$ is picked up to close front contact 5⁴ and apply a code pulse from the track battery 6⁴, energy is applied to the track circuit for actuating the code following track relay at the opposite end of the track circuit to one position through its inductive coupling as described in connection with either of the forms shown in Fig. 1, 2 or 3. At the end of such code pulse, the code transmitting relay $3CP^4$ is released and the back contact 5⁴ is closed to apply energy to the track circuit from the battery 40 of the opposite polarity. This causes a flow of current through the primary winding 9 of the transformer 2TF of Fig. 1, 2, or 3 in the reverse direction.

Since the reversal of current in the primary winding 9 tends to force the reversal of magnetic flux in the transformer core, it tends to cause a more rapid flux change to produce a pulse of increased amplitude in the secondary winding 10. Although this condition is present to some extent, its effectiveness is somewhat decreased due to the attenuating effect of the track circuit upon code pulses.

The more important feature of this form of the invention resides in the fact that the swing of the magnetic flux of the transformer from the peak of one polarity to the peak of the opposite polarity has an additive effect in producing a current pulse for operation of the track relay. Since this is true, it is apparent that the peak of each polarity need be only about one half the peak value required in Fig. 1 where only one polarity of current pulse is employed. This means that the energy applied for each code pulse by the contact 5⁴ of relay $3CP^4$ will be about half the energy value required for each pulse in Fig. 1. Thus, the front and back contacts 5⁴ each have to carry and break less current and will thereby last longer than when the organization of Fig. 1 is employed. In other words, the energy controlled by front contact 5 of Fig. 1 is divided between the front and back points of contact 5⁴ in Fig. 4. Since the normal current values are reduced by the addition of resistance to the resistors 7⁴ and 41, the same resistors act to limit the current flow during the occupancy of the track circuit by a train. This is a distinct advantage since rather heavy currents are caused to flow when a track circuit becomes occupied by a train and the breaking of such currents is very harmful to the coding contacts.

In brief, this form of the invention contemplated by Fig. 4 includes the application of pulses of opposite polarity applied to the track circuit without any substantial intervening time spaces between the pulses to give an additive effect upon the inductively coupled track relay in such a way as to permit the use of individual impulses of reduced energy levels to thereby reduce the wear on the code transmitting contacts both during

normal coding operations and when the track circuit is occupied by a train.

This form of the invention contemplated by Fig. 4 gives the same characteristic advantages provided by Fig. 1 in that it is immune to limited values of foreign current sometimes encountered in track circuits. In this connection, it might be noted that the reversal of polarity of the code pulses in the track circuit provides the same total swing from one peak value of current in the transformer winding 9 to the peak value of current of the opposite polarity regardless of the presence of a limited value of foreign current of either polarity. In other words, the particular value of foreign current present in the track circuit at any one time and flowing through the winding 9 merely furnishes a different baseline on the opposite sides of which the reversal of code pulse current can swing. Because of this, the total effect upon the track relay remains the same regardless of the presence or absence of such foreign current values.

It will thus be seen that a signalling system having its different track sections provided with track circuit apparatus organized in accordance with the present invention will be free of many of the troublesome conditions occurring in the conventional coded track circuits. For this reason, it is believed that the present invention is meritorious and represents a decided advantage over prior coded track circuit systems.

Having described several forms of a coded track circuit block signalling system employing code transmitting and receiving apparatus organized in accordance with the present invention to obviate difficulties in connection with foreign currents, and the like, as embodying the present invention, it is desired to be understood that the invention has been shown in these forms for the purpose of facilitating its disclosure and that the invention can be applied to coded track circuit systems of other types than the block signalling system shown. It is also to be understood that the specific embodiments of the invention may have various modifications, adaptations, and alterations made to the forms shown to meet the requirements of practice without in any manner departing from the spirit or scope of the present invention, except as limited by the appended claims.

What I claim is:

1. In a coded track circuit organization for railroads operable in spite of the presence of stray foreign potentials on the track rails, an insulated section of track, code transmitting means at one end of said section for applying sustained direct current code pulses at different code rates in accordance with traffic conditions, said code transmitting means causing said code pulses to have leading and trailing edges successively occurring at substantially equally spaced intervals, a code following track relay of the two-position type associated with the opposite end of said section, circuit means including a transformer for inductively coupling said relay to the rails of said section, said track relay being distinctively responsive to the polarity of its impulse energization from said transformer and effective to actuate and hold its contacts in opposite positions alternately in response to the successive impulses for the successive leading and trailing edges of said sustained direct current code pulses, and decoding means distinctively governed by the operation of said track relay to

its opposite positions at said different code rates for the control of wayside signals.

2. In a coded track circuit organization for railroads operable regardless of the possible presence of stray foreign potentials on the track rails, a section of track, code transmitting means at one end of said section for applying sustained direct current code pulses at different distinctive code rates in accordance with traffic conditions in advance, said code transmitting means causing said code pulses to have leading and trailing edges occurring in a continuous series at substantially equally spaced intervals, code receiving means at the other end of said track section including a transformer having primary and secondary windings mounted on a ferro-magnetic core with an air gap, said primary winding being connected across the rails of said track section, a polarized magnetic stick type relay connected across the secondary winding of said transformer, said relay having its contacts operated to one position by the current induced in said secondary winding for the leading edge of a code pulse and to the opposite position by the current induced in said secondary winding for the trailing edge of a code pulse, and decoding means distinctively controlled in accordance with the operation of said relay at a rate corresponding to the rate of the direct current code pulses applied to the track rails.

3. In a coded track circuit organization for railroads operable regardless of the possible presence of stray foreign potentials on the track rails, a section of track, code transmitting means at one end of said section for applying sustained direct current code pulses at different distinctive code rates in accordance with traffic conditions in advance, said code transmitting means causing said code pulses to have leading and trailing edges occurring in a continuous series at substantially equally spaced intervals, code receiving means at the other end of said track section including a transformer having primary and secondary windings mounted on the middle leg of an E-shaped ferro-magnetic core structure, said primary winding being connected across the rails of said track section, a polarized magnetic stick type relay connected to the secondary winding of said transformer, said relay having its contacts operated to one position by the current induced in said secondary winding for the leading edge of a code pulse and to the opposite position by the

current induced in said secondary winding for the trailing edge of a code pulse, and decoding means distinctively controlled by the substantially uniform operation of said relay in response to the inductive pulses applied to it at a rate corresponding to the rate of the direct current code pulses applied to the track rails.

4. In a coded track circuit organization for railroads operable regardless of the possible presence of stray foreign steady potentials on the track rails, an insulated section of track, code transmitting means at one end of said section for applying sustained direct current code pulses at different distinctive code rates in accordance with traffic conditions, said code transmitting means causing said code pulses to have leading and trailing edges successively occurring at substantially equally spaced intervals, a code following track relay of the two-position mechanical stay-where-put type having separate windings for actuating its contacts to their opposite positions, circuit means including a transformer having its secondary windings connected through oppositely poled rectifier units to the windings of said relay and having its primary winding directly connected to the track rails of said section to cause said relay windings to be alternately energized successively for the respective leading and trailing edges of the direct current code pulses applied to said track section, and decoding means distinctively governed in accordance with the rate of the operation of said two-position track relay to its opposite positions alternately.

J DONALD HUGHSON.
